United States Patent Office

Des. 182,189
Patented Feb. 25, 1958

182,189

RADIO CABINET

John W. Mason, Glenview, Ill.

Application April 5, 1957, Serial No. 45,605

Term of patent 14 years

(Cl. D56—4)

Fig. 1.

Fig. 3.

Fig. 2.

Fig. 1 is a front perspective view of a radio cabinet, showing my new design;

Fig. 2 is an end elevational view thereof, a portion having been broken away; and

Fig. 3 is a fragmentary front elevational view of the cabinet.

I claim:

The ornamental design for a radio cabinet, as shown.
